CLAIM

The ornamental design for an electric fence wire switch, as shown and described.

DESCRIPTION

FIG. 1 is a perspective view of an electric fence wire switch showing my new design;

FIG. 2 is a top plan view thereof;

FIG. 3 is a bottom plan view thereof;

FIG. 4 is a side elevation view thereof;

FIG. 5 is an opposite side elevation view thereof; and,

FIG. 6 is an end view thereof, the opposite end view being a mirror image.

The broken line showing in the figure drawings is included for illustrative purposes only and forms no part of the claimed design.
